8 Claims. (Cl. 318—401)

1

This invention relates to electric motor controllers. The object of the invention is the provision of improvements in electric motor controllers, particularly in respect of the timing of the intervals between the cutting out of resistance sections when starting.

With the above object in view according to the main feature of the invention a starting resistance for the motor is adapted to be cut out in steps by a master controlling device operating in conjunction with a motor driven timing relay which controls the time interval between the cutting out of successive sections of the starting resistance.

The system may include a set of contactors for cutting out the several starter resistance sections whose circuits are made ready for completion by the timing relay, by the completion of the main motor circuits in the case of the first contactor, and by the previous contactor in the case of subsequent contactors. Preferably the last contactor when in inoperative condition makes the circuit of the timing relay motor ready for completion by operation of the master controlling device, so that operation of said device sets the timing relay into operation, and the cutting out of the final resistance section stops the timing relay.

The invention also comprises an improved construction of timing relay which comprises a plurality of sets of stationary contact members which are alternately bridged by one or more bridging contacts moved at a predetermined speed by the timing relay motor. For example, the relay may comprise an insulating disc rotatable through worm gearing by a driving motor, said disc having contact rollers projecting from its surface and adapted to bridge sets of fixed contact fingers. For control purposes the motor shaft may carry an eddy current disc running in the magnetic gaps of one or more electromagnets energised by control windings.

For adjustment purposes the speed of running of the timing relay motor is adapted to be adjusted by a variable resistance, whilst for control purposes the speed of running of the timing relay motor is adapted to be controlled automatically by an electric device, which is de-energised until the final contactor is operated but upon opening of a switch by said contactor becomes energised, so as to stop the timing relay motor immediately its energising circuit is broken. The resistance contactor coil circuits are controlled alternately by successive sets of timing relay contacts, whilst preferably the rotor of the timing relay carries a bridging contact for a pair

2

of fixed contacts which replace the switch opened by the operation of the final resistance contactor and cause completion of the timing relay motor circuit through a braking coil. The timing relay 5 may also have its speed controlled by an electrical braking device connected across the last resistance section to be cut out, so as to decrease the speed of the timing relay with increase of motor load. Although the master controller may 10 be of push button or other type, it may with advantage be of the drum type, in which case its connections are such that the resistance contactors can only operate in consequence of corresponding movement of the drum and thus only 15 operate at time intervals determined by the timing relay.

In order that the invention may be more clearly understood and readily carried into practice, it is illustrated, by way of example only, by the accompanying drawings, in which:

Figure 1 is a circuit diagram of a D. C. motor control system according to the invention, and

Figure 2 is a perspective view of a construction of timing relay adapted for use in the control 25 system of Figure 1.

The invention is illustrated as applied to a direct current motor starter in which a master controller D_c of the drum type is employed. We provide a timing relay Tr driven by means of a 30 pilot motor P_m and adapted, so long as the pilot motor is running, alternately to bridge momentarily first one set of contacts $2, 4x$, then another set of contacts $1, 3x$, then the first set of contacts $2, 4x$ again, then the second set of contacts again, $1, 3x$, and so on. Normally (that is before 35 starting) the timing relay Tr is at rest with the first set of contacts $2, 4x$ bridged. When the main switch C is closed and drum controller D_c is moved to the first forward notch, a circuit through the drum is established via strip 5 , stud 6 , wires $7, 8$ and 9 , relay contacts 10 and 11 , which 40 energises two contactors C_1, C_2 in parallel. These accordingly close and thereby establish a circuit at contacts 12 and 13 through the motor armature A and all sections of starting resistance SR for starting the motor in the forward direction.

Contactor C_1 upon closing closes auxiliary contacts 14 and through these auxiliary contacts and 45 normally closed auxiliary contacts 15 on the contactor C_6 for cutting out the last of the resistance sections, an energising circuit for the pilot motor is established through variable resistance V_r and wires $16, 17, 18$ and 19 , independently of the drum 50 D_c and the pilot motor P_m commences to drive

the relay. Contactor C2, upon closing, also closes auxiliary contacts 20 but these at the moment effect nothing. But when, after a given time interval, the timing relay Tr reaches the position at which it bridges its second set of contacts 1, 3x a circuit is established energising the contactor C3 for cutting out the first of the resistance sections, said circuit extending from the positive main through the main switch C and drum contact 5, contact stud 6, wires 7, 8, through the auxiliary contacts 20 of contactor C2, back through the drum again, via wires 21, 22, contact stud 23, drum contacts 24, 25, wire 26, through the winding of contactor C3, wire 27, and across the contacts 1 and x of the said second set of timing relay contacts, and wires 18, 19 to the negative main.

Contactor C3 accordingly closes switch 35, cutting out the first resistance section and speeding up the motor one step. Contactor C3 upon closing closes auxiliary contacts 28 which establish a maintaining circuit via wires 29, 30 direct from the winding of contactor C3 to the negative main.

The contactor C3 upon closing also closes second auxiliary contacts 31, but so long as the drum remains at the first notch 1, nothing further happens. When the drum is moved to the second notch 2, nothing still happens until the next occasion upon which the timing relay Tr bridges its first set of contacts 2, 4x. When this takes place an energising circuit is established for the contactor C4 for cutting out the second of the resistance sections, said circuit extending from the positive main through the drum as before, through the auxiliary contacts 20 on contactor C2 as before, back to the drum as before, and, by fresh drum contacts 32, 33, closed when the second notch is reached, wire 34, through the energising winding of contactor C4, through the second auxiliary contacts 31 on contactor C3, and across the first and the last of the first set of timing relay contacts 2, x to the negative main.

Contactor C4 accordingly closes switch 36, cutting out the second resistance section and speeding up the motor another step. Contactor C4 upon closing closes auxiliary contacts 37 which establish a maintaining circuit direct from the winding of contactor C4 to the negative main via wires 29, 30.

The contactor C4 upon closing also closes second auxiliary contacts 38, but so long as the drum remains at the second notch 2, nothing further happens. When the drum is moved to the third notch 3, nothing still happens until the next occasion upon which the timing relay Tr bridges its second set of contacts 1, 3x. When this takes place an energising circuit is established for the contactor C5 for cutting out the third of the resistance sections, said circuit extending from the positive main through the drum as before, through the auxiliary contacts 20 on contactor C2 as before, back to the drum as before, and, by fresh drum contacts 39, 40, closed when the third notch is reached, wire 41, through the energising winding of contactor C5, through the second auxiliary contacts 38 on contactor C4, and across the second and the last of the second set of timing relay contacts 3, x to the negative main.

Contactor C5 accordingly closes switch 42, cutting out the third resistance section and speeding up the motor another step. Contactor C5, upon closing closes auxiliary contacts 43 which establish a maintaining circuit direct from the

winding of contactor C5 to the negative main. Contactor C5, upon closing, also closes second auxiliary contacts 44, but so long as the drum remains at the third notch, nothing further happens. When the drum is moved to the fourth notch 4, nothing still happens until the next occasion upon which the timing relay Tr bridges its first set of contacts 2, 4x. When this takes place an energising circuit is established for the contactor C6 for cutting out the fourth of the resistance sections, said circuit extending from the positive main through the drum as before, through the auxiliary contacts 20 on contactor C2 as before, back to the drum as before, and, by fresh drum contacts 45, 46, closed when the fourth notch is reached, wire 47, through the energising winding of contactor C6, through the second auxiliary contacts 44 on contactor C5, and across the second and the last of the first set of timing relay contacts 4, x to the negative main.

Contactor C6 accordingly closes switch 48, cutting out the fourth resistance section. Contactor C6, upon closing, closes auxiliary contacts 49 which establish a maintaining circuit direct from the winding of contactor C6 to the negative main.

In the present description contactor C6 is assumed to be the last of the resistance contactors, but it will be quite clear from the preceding description that the number of resistance contactors could be increased indefinitely by adding to the number of timing relay contacts in each of the aforesaid first and second sets 2, 4x and 1, 3x respectively.

When the last contactor C6 closes, it opens the normally closed auxiliary contacts 55 hereinbefore referred to, and interrupts the aforescribed energising circuit for the pilot motor Pm of the timing relay Tr. There is, however, a second circuit for energising the said pilot motor. This second circuit is in parallel with the circuit passing in series through the auxiliary contact on the contactor C6 and the auxiliary contacts on the contactor C1, and includes, in series, a cut-out switch 50 on the timing relay and the winding of a brake 51 which, when energised exercises a drag on the pilot motor. The cut-out switch 50 is normally closed and is only opened when the timing relay Tr is at the position for bridging its first set of contacts.

It will therefore be seen that normally, before starting, this second circuit is interrupted at the cut-out switch 50. After the pilot motor Pm has been energised through the auxiliary contacts 14, 15, on contactors C1 and C6, this second circuit will be closed except at those moments when the timing relay Tr is bridging its first set of contacts 2, 4x but it is, however, short circuited by the said auxiliary contacts 14, 15, so that the brake winding remains de-energised. When the auxiliary contact 15 on contactor C6 opens, the timing relay Tr will continue by momentum to move until the cut-out switch 50 closes and the pilot motor Pm will now be energised through its said second circuit which includes the winding of brake 51. The result of this is that the pilot motor Pm will run dead slow, due to the drag exercised by the brake 51, and when the timing relay Tr again reaches the position at which the contacts of its first set 2, 4x are bridged, and at which the cut-out switch 50 opens, said pilot motor Pm will instantly stop and the timing relay Tr will not over-run this position. Thus it is ensured that the timing relay Tr will always come to rest at the correct starting position.

It will be appreciated from the preceding description that, if the drum controller Dc is moved straight from the off position to the last notch 4, the contactors C1—C6 will close in the same sequence, with an interval, before the cutting out of each resistance section, determined by the time taken for the timing relay Tr to move from one bridging position to the other. Thus the contactors C1 and C2 will instantly close; the contactor C3 will close when first the second set of timing relay contacts 1, 3x are bridged; the contactor C4 will close when next the first set of timing relay contacts 2, 4x are bridged; the contactor C5 will close when next the second set of timing relay contacts 1, 3x are bridged, and the contactor C6 will close when next the first set of timing relay contacts 2, 4x are bridged.

It will also be noted that when the drum controller Dc is notched backwards, the contactors will drop out instantaneously according to the drum positions without any delay occasioned by the timing relay Tr. It will be noted, however, that the timing relay Tr will be driven when the drum is notched back, until said drum reaches the off position, when the contactor C1 will drop out, opening its auxiliary contact 14 and de-energising the first circuit of the pilot motor Pm, and the pilot motor will then be energised through its second circuit, at slow speed with the brake 51 on, until the timing relay Tr next reaches the starting position, when the cut-out switch 50 will open and the timing relay Tr will instantly stop at its starting position.

When the drum controller Dc is notched in the reverse direction the operation is exactly the same, except that instead of the contactors C1 and C2 closing, two other contactors C1a and C2a, will close, thereby establishing circuits for reverse running. Otherwise, these contactors C1a and C2a function in the same way as the contactors C1 and C2, and the same contactors C3 to C6 operate for controlling the resistance sections. The pilot motor Pm of the timing relay Tr will of course always run in the same direction.

The main operating circuit of the motor is controlled by main switch C through the normally closed circuit breaker, CB which operates in the normal manner in conjunction with the usual overload and no voltage releases.

The speed of the pilot motor Pm is adapted to be pre-set over a wide range by connecting one terminal thereof to one end of the resistance Vr and the other terminal to a variable tapping point of said resistance Vr.

The speed of said pilot motor Pm is also adapted to be automatically controlled by means of a control winding 70 which, according to its intensity of energisation, exercises a drag on said pilot motor. This control winding is connected by wires 19 and 71 across part of the series resistance SR of the main motor, viz across the last resistance section to be cut out, and thus, during the whole of the starting period up to the closure of the last resistance contactor C6, the energisation of said control winding will vary as the load of the main motor varies, so that the greater the load on the main motor, the slower the speed of the pilot motor Pm and timing relay Tr and the longer the minimum intervals between the cutting out of successive sections of resistance SR.

It will be readily appreciated that the direct current system above described can be readily replaced by an alternating current system, the timing relay Tr functioning in exactly the same way. No further description of this is deemed neces-

sary. It will also be appreciated that the drum controller DC could be dispensed with and the starter controlled by push button switches, the timing of the cutting out of the resistance sections then depending solely upon the timing relay Tr, much in the same way as if the drum controller were moved straight through to the last notch.

In the case of direct current systems only, an alternative method of automatic control of the speed of the pilot motor Pm can be adopted. This consists in connecting the pilot motor across the armature A and part of the starting resistance SR of the main motor. The speed of the pilot motor Pm will be controlled by the back electromotive force of the armature A of the main motor, and the speed of said pilot motor Pm will vary inversely with the loading of the main motor. The reason for using part of the starting resistance SR is to ensure that the pilot motor will run when the main motor is at a standstill. Resistance will thus be cut out if the main motor fails to start.

In the case of alternating current systems the aforescribed control winding for the pilot motor can be connected, either direct or through a current transformer in series with one of the starter feeders.

It will be seen that in this invention, except for the timing relay Tr, no special apparatus is used, and the contactors are all standard contactors with no special attachments.

Also the timing relay is universal in its application, the same timing relay serving whether with alternating or direct current schemes or whether the system embodies a master controller or is push button operated. Again the timing relay has no operating system but simply continues to bridge its two sets of contacts alternately.

In a preferred construction illustrated by Figure 2, the timing relay Tr comprises a rotatable worm wheel 52, which may be made of synthetic resin, driven through the medium of a worm 53 on the shaft 54 of the pilot motor. This worm wheel 52 has projecting at right angles from it, at a given distance from its centre, a bridging contact in the form of an elongated roller 55 rotatably mounted on a suitable fixed pin 56. Each set of timing relay contacts 2, 4x or 1, 3x consists of a row of leaf-spring type contacts 57 parallel to each other and all at right angles to the bridging contact 55, so that it simultaneously engages all these when it reaches the appropriate position. The two sets of timing relay contacts are of course diametrically opposite to each other, so that, assuming the pilot motor to be running at a constant speed, the time intervals between the bridging of the two sets are equal.

Instead of only one bridging contact 55, the worm wheel may be provided with three located at one hundred and twenty degrees to each other, and two of these may be detachable so that the worm wheel 53 may have either one, two or three. Obviously, if there are three, it simply means that the bridging of the two sets of timing relay contacts takes place at thrice the frequency, and this gives an additional control to the timing of the starter which, in conjunction with the pilot motor resistance Vr hereinto before referred to, affords a very wide range of pre-set timing control.

The cut-out 50 may consist simply of a leaf-spring contact 58 biased into engagement with a relatively stationary contact 59 and adapted to be engaged by a cam 60 on the worm wheel, and lifted clear of said relatively stationary contact

59, when said worm wheel reaches the appropriate position. It will of course be appreciated that the opening of said cut-out switch 50 persists through several degrees of movement of the worm wheel 52, and the same applies to the bridging of the sets of timing relay contacts 2, 4x and 1, 3x.

For applying the afore-described brake 51 to the pilot motor Pm an aluminum eddy current disc 61 is mounted on the motor shaft 54, and the brake winding 62 energises a magnet frame 63 having a gap in which the eddy current disc runs.

The afore-described control winding 70, if such is employed, may, as indicated by the chain dotted lines in Figure 2, energise a magnet frame similar to that energised by the brake winding 51 and having a gap in which the same eddy current disc 61 runs. In the case of a direct current system, this control winding is energised as previously described. In the case of an alternating current system, the control winding may be connected across part of the starting resistance or across two slip ring phases.

The pilot motor Pm is arranged to be considerably under-loaded, and is preferably a series commutator machine suitable for running on either alternating or direct current.

It will be appreciated that the timing relay Tr is essentially nothing but a change over switch with multiple contacts, and thus it may take forms other than the motor driven arrangement described. For example, it could take the form of an electro-magnet with time delay, each impulse of which operates a multiple change-over switch.

We claim:

1. In an electric motor control system, a main motor, resistance sections in circuit with said main motor, electromagnetic contactors having energising windings and adapted, upon energisation of said windings, to close and thereby respectively cut out said resistance sections, a pilot motor, a timing relay driven by said pilot motor, said timing relay comprising a plurality of contacts which correspond respectively to said contactors, said relay contacts being divided into sets, which sets are adapted to close in cyclic order repeatedly as said timing relay is driven by said pilot motor, means for energising said pilot motor with the resistance sections all in circuit with the main motor, means whereby, each time a set of relay contacts close, which set includes the contact corresponding to the contactor next due to close, the winding of said contactor is energised, means whereby, upon a contactor closing, its winding is maintained energised independently of its corresponding relay contact, and means whereby, upon closure of the contactor last due to close, said pilot motor is automatically brought to rest with said timing relay at a given starting position.

2. In an electric motor control system, a main motor, resistance sections in circuit with said main motor, electromagnetic contactors having energising windings and adapted, upon energisation of said windings, to close and thereby respectively cut out said resistance sections, a pilot motor, a timing relay driven by said pilot motor, said timing relay comprising a plurality of contacts which correspond respectively to said contactors, said relay contacts being divided into sets, which sets are adapted to close in cyclic order repeatedly as said timing relay is driven by said pilot motor, means for energising said pilot motor with the resistance sections all in circuit with the main motor, means whereby, each time a set of relay contacts close, which set includes the con-

tact corresponding to the contactor next due to close, the winding of said contactor is energised, means whereby, upon a contactor closing, its winding is maintained energised independently of its corresponding relay contact, and means whereby, upon closure of the contactor last due to close, said pilot motor is automatically brought to rest with said timing relay at a given starting position, said last named means comprising two circuits through which said pilot motor is adapted to be energised, one of said circuits being interrupted upon closure of said contactor last due to close and the other being interrupted upon said timing relay reaching said starting position.

3. In an electric motor control system, a main motor, resistance sections in circuit with said main motor, electromagnetic contactors having energising windings and adapted, upon energisation of said windings, to close and thereby respectively cut out said resistance sections, a pilot motor, a timing relay driven by said pilot motor, said timing relay comprising a plurality of contacts which correspond respectively to said contactors, said relay contacts being divided into sets, which sets are adapted to close in cyclic order repeatedly as said timing relay is driven by said pilot motor, means whereby, each time a set of relay contacts close, which set includes the contact corresponding to the contactor next due to close, the winding of said contactor is energised, means whereby, upon a contactor closing, its winding is maintained energised independently of its corresponding relay contact, and means whereby the speed of said pilot motor is adapted to be increased and decreased, according as the armature current of the main motor decreases and increases.

4. In an electric motor control system, a main motor, resistance sections in circuit with said main motor, electromagnetic contactors having energising windings and adapted, upon energisation of said windings, to close and thereby respectively cut out said resistance sections, a pilot motor, a timing relay driven by said pilot motor, said timing relay comprising a plurality of contacts which correspond respectively to said contactors, said relay contacts being divided into sets, which sets are adapted to close in cyclic order repeatedly as said timing relay is driven by said pilot motor, means whereby, each time a set of relay contacts close, which set includes the contact corresponding to the contactor next due to close, the winding of said contactor is energised, means whereby, upon a contactor closing, its winding is maintained energised independently of its corresponding relay contact, and a braking winding for said pilot motor, the energisation of which winding increases and decreases, according as the armature current of the main motor increases and decreases whereby the speed of said pilot motor is adapted to be increased and decreased, according as the armature current of the main motor decreases and increases.

5. In an electric motor control system, a main motor, resistance sections in circuit with said main motor, electromagnetic contactors having energising windings and adapted, upon energisation of said windings, to close and thereby respectively cut out said resistance sections, a pilot motor, a timing relay driven by said pilot motor, said timing relay comprising a plurality of sets of contacts, said plurality of sets together having a number of contacts corresponding in number to said contactors, and said plurality of sets being adapted to be closed in cyclic order repeatedly by

rotation of said pilot motor, means whereby the winding of each of said contactors is energised in response jointly to the closure of the relay contact of corresponding number and the closure of the preceding contactor, and means whereby, upon a contactor closing, its winding is maintained energised independently of the relay contact of corresponding number.

6. In an electric motor control system, a main motor, resistance sections in circuit with said main motor, electromagnetic contactors having energising windings and adapted, upon energisation of said windings, to close and thereby respectively cut out said resistance sections, a pilot motor, a timing relay driven by said pilot motor, said timing relay comprising a plurality of sets of contacts, said plurality of sets together having a number of contacts corresponding in number to said contactors, and said plurality of sets being adapted to be closed in cyclic order repeatedly by rotation of said pilot motor, means whereby the winding of the first contactor is energised in response to the closure of the first relay contact, means whereby the winding of each of the other contactors is energised in response jointly to the closure of the relay contact of corresponding number and the closure of the preceding contactor, and means whereby, upon a contactor closing, its winding is maintained energized independently of the relay contact of corresponding number.

7. In an electric motor control system, a main motor, resistance sections in circuit with said main motor, electromagnetic contactors having energising windings and adapted, upon energisation of said windings, to close and thereby respectively cut out said resistance sections, a pilot motor, a timing relay driven by said pilot motor, said timing relay comprising two sets of contacts, the two sets together having a number of contacts corresponding in number to said contactors, and said two sets being adapted to be alternately opened and closed by rotation of said pilot motor, means whereby the winding of the first contactor is energised in response to the closure of the first relay contact, means whereby the winding of each of the other contactors is energised in response jointly to the closure of the relay contact of corresponding number.

5 tact of corresponding number and the closure of the preceding contactor, and means whereby, upon a contactor closing, its winding is maintained energised independently of the relay contact of corresponding number.

8. In an electric motor control system, a main motor, resistance sections in circuit with said main motor, electromagnetic contactors having energising windings and adapted, upon energisation of said windings, to close and thereby respectively cut out said resistance sections, a master controller of the drum type having an off notch and a number of running notches corresponding in number to said contactors, a pilot motor, a timing relay driven by said pilot motor, said timing relay comprising two sets of contacts, the two sets together having a number of contacts corresponding in number to said contactors, and said two sets being adapted to be alternately opened and closed by rotation of said pilot motor, means whereby the winding of the first contactor is energised in response jointly to the closure of the first relay contact and the positioning of said master controller at a running notch, means whereby the winding of each of the other contactors is energised in response jointly to the closure of the relay contact of corresponding number, the closure of the preceding contactor, and the positioning of the master controller beyond the notch of preceding number and means whereby, upon a contactor closing, its winding is energised independently of the relay contact of corresponding number.
